CLAIM

The ornamental design for a teether, as shown and described.

DESCRIPTION

FIG. 1 is a top front perspective view of a teether showing our new design.

FIG. 2 is a bottom rear perspective view thereof;

FIG. 3 is a rear elevational view thereof;

FIG. 4 is a front elevational view thereof;

FIG. 5 is a right side elevational view thereof;

FIG. 6 is a left side elevational view thereof;

FIG. 7 is a top plan view thereof; and,

FIG. 8 is a bottom plan view thereof.

In the drawings, the broken lines depict environmental structure only and form no part of the claimed design.

1 Claim, 6 Drawing Sheets
